Inventor:

Henry F. Belcher
By Francis W. Parker,
Attorney.

UNITED STATES PATENT OFFICE.

HENRY F. BELCHER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,972, dated December 7, 1897.

Application filed November 1, 1897. Serial No. 657,106. Term of patent 14 years.

To all whom it may concern:

Be it known that I, HENRY F. BELCHER, a citizen of the United States, residing at Chicago, in the county of Cook and State of Illinois, have invented a certain new and original Design for Prism-Lights, of which the following is a specification.

My invention relates to designs for prism-lights.

10 Figure 1 is a plan view of a prism-light embodying my design. Fig. 2 is a cross-section therethrough.

15 A is the body of the prism-light; B, one side thereof; C C, a series of fractured prisms on the other side thereof, and D D indicate the somewhat irregularly bordered, recessed, or hollowed-out surfaces formed upon such frac-

tured prisms. The work is called "fracto-work."

The essential features of my design are 20 found in a prism-light comprising a substantially flat thin body with a series of prisms wholly mutilated or fractured, so as to present regularly-distributed rows of irregularly bordered, recessed, or hollowed-out surfaces, 25 as shown.

I claim—

A design for a prism-light, substantially as shown and described.

HENRY F. BELCHER.
